Inventor:
Samuel Ellis,

By his Attorney, Leo McNeilly

Patented Feb. 15, 1927.

1,617,580

UNITED STATES PATENT OFFICE.

SAMUEL ELLIS, OF BROOKLYN, NEW YORK.

SANITARY PROTECTOR FOR STEMS OF TOBACCO PIPES, CIGAR HOLDERS, ETC.

Application filed August 31, 1926. Serial No. 132,738.

The object of my invention is to afford simple but effective sanitary means for the protection of the stems and mouth pieces of smokers' tobacco pipes and cigar holders when the same are not in actual use, in such manner that dirt, dust, and extraneous matter will be excluded from contact therewith, all as hereinafter fully set forth,—the invention consisting in the specific construction and arrangement of the device shown, described and claimed herein, and an incidental feature being its adaptability to stems of various shapes and sizes, thereby the protector is available, as an article of manufacture, for general use.

In the accompanying drawings I illustrate a practical embodiment of the essential features of my invention as adapted to the protection of smokers' pipe stems and cigar holders, although I do not restrict myself to the identical configuration of parts thereof, shown by way of exemplification, since changes may be made in minor details and equivalent expedients resorted to with like results, and without departing from the spirit and intent of my invention in this respect.

With this understanding,

Fig. 1 represents a top view of a tobacco pipe to the stem of which my protector is applied;

Fig. 2 is a side elevation of the parts shown in Fig. 1;

Fig. 3 is a view similar to Fig. 1, showing my protector as applied to smaller pipe and stem;

Fig. 4 is a longitudinal section of the protector taken upon plane of line 4—4, Fig. 2;

Fig. 5 is a transverse section of the protector taken upon plane of line 5—5, Fig. 1;

Fig. 6 is a perspective view of the protector;

Fig. 7 is a view like unto Fig. 3, but showing the protector as applied to the mouth piece of a cigar holder.

My protective device for the use of smokers consists primarily of a socket piece or receptacle constituting practically a cap C, adapted to fit over the mouth piece and adjacent portion of the stem of a tobacco pipe P, or of a cigar holder H, as indicated in Figs. 1, 2, 3 and 7, of the drawings; and secondarily, in forming said cap C, with a foldable extension c, which may be inturned as shown in Figs. 3 and 7, of the drawings, for the purpose of compensating for differ-

ences in the size and shape of the pipe stems or mouth pieces of cigar holders, etc., to which the device may be applied, and insuring a close contactual fit of the parts involved.

My protector is a one-piece, unitary structure of elastic resilient rubber, cast, pressed or moulded into requisite shape by means well known in the art of manufacture of analogous rubber goods.

The rear end c', of the protector is closed, and relatively thick to stiffen the structure and afford a firm finger hold for manipulative purposes. Also, for the purpose of facilitating manipulation, and reinforcing the front end of the receptacle C, it is formed with an annular collar c², around the insert opening c³ (Fig. 4),—said collar affording a finger hold conveniently available in the application or removal of the device as related to the mouth piece and stem of the article in conjunction with which it may be used.

The foldable extension or wedge insert c, of the protector projects from the annular collar c², as a base, the outer portion tapering toward the contracted end c⁴, and the outer side of said extension being formed with a groove c⁵, to conform to the shape of the adjacent portion of a pipe or holder stem when the latter is inserted between the inturned extension c, and the opposed inner side of the protector, as illustrated in Figs. 3 and 7, of the drawings.

It will be readily understood that by the use of my auxiliary detachable protective cap C, a pipe stem mouth piece, or that of a cigar holder, etc., may be effectually safeguarded against soiling or contamination by extraneous objects or matter, the elastic resilience of the rubber of which the protector is formed insuring a close fit and contactual engagement of surfaces to the exclusion of dust, dirt, etc., so that the smokers' utensil thus equipped may be carried in the pocket, or otherwise disposed of when not in actual use, and this in a manner essentially sanitary, applying even to manipulation. When thus sealed, intrusion of any substance into the bore or tube of a mouth piece is rendered impossible, so that the user is assured a clear, clean smoke when desired.

Furthermore, the protector, being made of non-absorbent, washable rubber of smooth surface may readily be kept clean and sanitary upon occasion.

What I claim as my invention and desire to secure by Letters Patent is:

1. As an article of manufacture, a sanitary protector of the character designated, consisting of an elastic resilient cap formed with an insert extension, for the purpose set forth.
2. As an article of manufacture, a sanitary protector of the character designated, consisting of an elastic resilient cap formed

with a grooved insert extension, for the purpose set forth.

3. As an article of manufacture, a sanitary protector of the character designated, consisting of an elastic resilient rubber cap formed with a relatively thick closed rear end, with an annular collar around its open end, and with a grooved insert extension, as and for the purpose set forth.

SAMUEL ELLIS.
